US00D886236S

(12) **United States Design Patent** (10) **Patent No.:** **US D886,236 S**
Pfund et al. (45) **Date of Patent:** **** Jun. 2, 2020**

(54) **HOUSING FOR MULTIPLE VALVES**

(71) Applicant: **Bradley Fixtures Corporation**,
Menomonee Falls, WI (US)

(72) Inventors: **Ryan Pfund**, Menomonee Falls, WI
(US); **Heming Dai**, Menomonee Falls,
WI (US)

(73) Assignee: **Bradley Fixtures Corporation**,
Menomonee Falls, WI (US)

(**) Term: **15 Years**

(21) Appl. No.: **29/647,856**

(22) Filed: **May 16, 2018**

(51) LOC (12) Cl. **23-01**

(52) U.S. Cl.

USPC **D23/233**

(58) **Field of Classification Search**

USPC D23/233

CPC E03B 7/09; F16K 19/006

(57) **CLAIM**

We claim the ornamental design for a housing for multiple valves, as shown and described.

DESCRIPTION

FIG. 1 is a front, right, perspective view of the claimed design additionally showing an exemplary pair of valves attached to the housing;

FIG. 2 is a front, right, perspective view of the claimed design of FIG. 1;

FIG. 3 is a front side view of the claimed design of FIG. 1;

FIG. 4 is a rear side view of the claimed design of FIG. 1;

FIG. 5 is a right side view of the claimed design of FIG. 1;

FIG. 6 is a left side view of the claimed design of FIG. 1;

FIG. 7 is a top view of the claimed design of FIG. 1; and,

FIG. 8 is a bottom view of the claimed design of FIG. 1.

The broken lines illustrate environmental structure and form no part of the claimed design.

1 Claim, 7 Drawing Sheets
